UNITED STATES PATENT OFFICE.

CLARENCE P. BYRNES, OF SEWICKLEY, PENNSYLVANIA.

MOTOR-COOLING SYSTEM.

Application filed June 3, 1918. Serial No. 237,678.

To all whom it may concern:

Be it known that I, CLARENCE P. BYRNES, a resident of Sewickley, Allegheny County, Pennsylvania, have invented a new and useful Improvement in Motor-Cooling Systems, of which the following is a full, clear, and exact description; reference being had to the accompanying drawings, forming part of this specification, in which—

10 Figure 1 is a side elevation partly in section showing one form of my invention;

Figure 2 is a detail longitudinal section of the air injector system;

15 Figure 3 is a cross section on the line III—III of Figure 2; and

Figure 4 is a view similar to Figure 2, showing a modified form.

The invention relates to motor-cooling systems in which air is drawn through the 20 radiator for cooling water by means of the exhaust from the internal combustion engine.

The main object of my invention is to provide for varying the amount of air 25 drawn through the radiator, this being under the control of the operator from the dash or seat on the vehicle. Where a motormeter or any device for indicating the engine temperature is employed, the operator can vary the cooling effect of the air 30 on the water, and thus vary the temperature of the engine as desired.

In the drawings, 2 indicates the radiator and 3 the internal combustion motor of an 35 automobile of ordinary type having the usual fly wheel 4, a starter being shown at 5.

At the rear of the radiator is placed an air chamber or chambers shown as separated by a vertical partition 6, these chambers extending vertically in front of the engine and extending downwardly to an air pipe or pipes 7, forming part of an injector system. 8 is the exhaust pipe from the exhaust manifold 9, the exhaust 40 gases passing from this pipe into the pipe 10 and sucking in air from the pipe 7. Surrounding the end portion of the injector pipe 8 is a rotary valve 11, having suitable slots through which air may be 45 drawn in by the injector action of the exhaust gases, these slots registering with slots in the pipe 10. This valve may be turned by a projecting pin 12, having suitable connections indicated at 13, leading to 50 a point within the driver's reach.

In the case of a V-shaped engine, there

are preferably two vertical compartments or air chambers separated by a partition 6, in the rear of the radiator, dividing the radiator in half in a vertical direction. Each 50 of these extends down to the lower part of the radiator where it merges into a pipe extending below and at one side of the engine. The system will thus be symmetrical on each side, the pipes 10 extending back on either 55 side of the fly wheel to a muffler or mufflers. In the case of an ordinary engine, the exhaust may be branched so as to lead the injector pipe down on each side of the engine with a partition in the air chamber making 60 it a two-compartment chamber, or the exhaust may be led down on one side of the chamber, making a single chamber covering the whole rear of the radiator.

In either case, the engine compartment 65 need not be air-tight, and access is afforded to it through the ordinary movable sides of the hood.

Other types of valves may be used for varying the amount of air drawn in. Thus, 70 instead of throttling the air entrance to the injector, I may vary the efficiency of the injector pipe. Thus, in Figure 4, I show the injector pipe 8^a as having a stationary control valve 14 and a sliding sleeve 15, 75 having a conical end portion 16, which may be adjusted toward and from the cone-shaped valve through the lever 17, connected to the driver's compartment. In this figure, 7^a represents the air pipe from the 80 air chamber or chambers back of the radiator.

The advantages of my invention result from the means for varying the amount of air drawn through the radiator. This 85 adjustment can be made while the vehicle is in motion, and the operator by watching the motormeter or other indicator can vary the amount of air drawn through the radiator, and thus keep the motor at its 90 most efficient temperature. In winter weather, the air valve of the injector system can be closed, if desired. Furthermore, by carrying the air chamber downwardly to a conduit or conduits below the engine, the 95 engine chamber need not be air-tight and the engine is easily accessible.

I claim:

1. In a cooling system for motor vehicles, a radiator connected with the water-cooling 100 system of a motor, a motor exhaust injector system arranged to draw air through

- the radiator, and means for varying the amount of air drawn from the radiator by the injector system without obstructing or varying the exhaust passage for the gases.
- 5 2. In a cooling system for motor vehicles, a radiator connected with the water-cooling system of a motor, an air chamber at the rear of the radiator, an air pipe leading backwardly from the air chamber, a motor exhaust injector system arranged to draw air through the air pipe, and means for varying the amount of air drawn from the radiator by the injector system without obstructing or varying the exhaust passage for the gases.
- 10 3. In a cooling system for motor vehicles, a radiator connected with the water-cooling system of a motor, an air chamber at the rear of the radiator, an air pipe extending rearwardly from the air chamber and having a portion of decreasing cross-sectional area, a motor exhaust injector system ar-
- ranged to discharge the exhaust into the decreasing area portion of the air pipe and means operable by the driver of the vehicle while it is in motion for decreasing the efficiency of the injector while maintaining a full area of the exhaust passage for gases, substantially as described.
4. In a cooling system for motor vehicles, a radiator connected with the water cooling system of a motor, a motor exhaust injector system having an exhaust pipe leading directly from the motor to the injector system and arranged to draw air through the radiator, and means for variably restricting the amount of air drawn through the radiator by the injector system while maintaining full area of the exhaust, substantially as described.
- 25 30 35
- In testimony whereof, I have hereunto set my hand.
- CLARENCE P. BYRNES.
